UNITED STATES PATENT OFFICE.

CLARENCE E. BAUMER AND BERTHA BAUMER, OF TROY, OHIO.

SAFETY DEVICE FOR ELEVATORS.

1,018,864.

Specification of Letters Patent. Patented Feb. 27, 1912.

Application filed February 12, 1910. Serial No. 543,459.

To all whom it may concern:

Be it known that we, CLARENCE E. BAUMER and BERTHA BAUMER, citizens of the United States of America, residing at Troy, in the county of Miami and State of Ohio, have invented certain new and useful Improvements in Safety Devices for Elevators, of which the following is a specification, reference being had therein to the accompanying drawing.

This invention relates to safety devices for elevator cars, and the principal object of the same is to provide automatically acting means that will cause the car to descend slowly in the event of the hoisting cable thereof becoming broken. In addition to the foregoing the invention contemplates the provision of manually controlled means for said automatically acting means whereby in the event of the hoisting cable slipping, the automatically acting means may be manually actuated to cause the descent of the car to be slow. And further, the invention contemplates the employment of means actuated by an open door of the car for causing the automatically acting means to control the descent of the car.

In carrying out the objects of the invention generally stated above it is understood, of course, that the essential features thereof are necessarily susceptible of changes in details and structural arrangements, certain preferred and practical embodiments of which are shown in the accompanying drawings, wherein:—

Figure 1 is a view in vertical section of an elevator well, a car, and its hoisting mechanism, showing one embodiment of the safety device. Fig. 2 is a detail view in side elevation of the rack gripping mechanism for controlling the descent of the car. Fig. 3 is a view in elevation of one end of said mechanism. Fig. 4 is a vertical longitudinal sectional view of the combined core and air cushions for the rack gripping mechanism. Fig. 5 is a view similar to Fig. 1, but showing a variation of the invention. Fig. 6 is a vertical longitudinal sectional view of the rack gripping mechanism used in connection with the structure shown in Fig. 5. Fig. 7 is a detail perspective view of a door operated circuit breaker for automatically operating the rack gripping mechanism when the car door is open. Fig. 8 is a detail view in side elevation of a combined manually operated and an open door oper-

ated circuit breaker shown in connection with the form of the invention illustrated in Fig. 5.

Referring to the accompanying drawings by numerals, and more particularly to Figs. 1, 2, 3 and 4 thereof, 1—2 designate the walls of the well which are provided with the usual vertical racks 3—4. Beams 5 span the top of the well and support the bearings 6 in which shaft 7 of pulley 8 is mounted. The elevator car 9 has supporting beams 10 at its top to which the usual cable fastener 11 is attached. A hoisting cable 12^a extends from fastener 11 to and over pulley 8 in a manner well understood.

A combined core magnet and cushion 12 is mounted upon beams 10, said magnet being provided with a centrally located transverse partition 13 which divides the interior of the magnet into two compartments 14—15. The outer end of each compartment has a head 16 fitted air tight thereto, said head being provided with a central outstanding bearing 17 through which a piston rod 18 slides, the inner end of said rod being equipped with a piston 19. Each head is also provided with a pipe 20 that communicates with the compartments, the outer end thereof being equipped with a controlling valve 21. Adjacent their inner end, each compartment is equipped with another outwardly projecting pipe 22 provided at its outer end with a controlling valve 23.

Beams 10 are arranged on the car 9 so that their ends project toward the well racks 3—4, and the core magnet 12 is arranged longitudinally of said beams so that the ends thereof also project toward said racks. The ends of said beams have a flat slideway 24 thereon the sides 25 of which flare outwardly, and each slideway is engaged by a plate 26 having a longitudinal recess 27 formed in its bottom that conforms to the shape of said slideway, so that said plates may be slidably fitted over said slideways. A pair of spaced apart standards 28 are mounted on each plate 26, each pair of standards supporting a shaft 29 one end of which has a gear wheel 30 mounted thereon, the other end of said shaft having a disk 31 mounted thereon, said disks being smaller in diameter than gear wheels 30. Each disk 31 has one end of a link rod 32 eccentrically pivoted thereto, said link having its other end pivotally connected to the outer

end of the piston rod 18 that is adjacent thereto. Piston rods 18 project beyond the ends of the core magnet, and each have a collar 33 loose thereon to which one end of a link 34 is pivotally connected, said link having its other end pivotally connected to a rod 35 slidably mounted in a guide 36 projecting from one of the beams 10, said rod 35 having its other end connected to plate 26. Between their guide 36 and their connection with plates 26, rods 35 have an abutment 37 on them, and a spring 38 is coiled about each rod, one end of said spring bearing against abutment 37 and the other end against guide 36. Said springs 38 are of the expansible type and constantly exert a pressure tending to force their rods 35 away from the core magnet so that plates 26 will slide outward on their slideway and cause the gear wheels 30 to engage the well racks 3—4.

A supporting and guiding frame 39 is mounted in one wall of the car 9 and has a bar 40 slidably mounted therein. Said bar has one end projecting through the wall of the car and equipped with a roller 41 that is normally held in contact with a conductor rod 42 that is arranged parallel with well racks 3 by means of the pressure of a spring 43 that is wound upon bar 40 and has one end bearing against an abutment pin 44 that passes transversely through bar 40, the other end of said spring bearing against said frame 39. The inner end of bar 40 is equipped with an insulated handgrip 40^a that projects into the car 9 so that the operator may grasp said handle and slide bar 40 in its frame against the tension of spring 43 to withdraw roller 41 from contact with conductor rod 42.

A plate 45 is carried by the floor of car 9, said plate being of non-conducting material and having a conductor strip 46 set in one end portion thereof. A binding post 47 is carried by said strip 46. A pair of standards 48 are mounted on plate 45, said standards supporting a shaft 49 on which a circuit closing lever 50 is mounted, one end of said lever being provided with a contact lug 51. The contact end of lever 50 is provided with a binding post 52, and adjacent said contact end, a spring 53 connects lever 50 with plate 45 and exerts a pressure tending to hold the contact end of lever 50 in contact with strip 46. The other end of lever 50 is provided with a tripping arm 54 that is in the path of movement of the door 55 of car 9 so that when said door is open, its lower edge will contact with arm 54 and rock lever 50 to raise its lug 51 from strip 46 against the tension of spring 53.

A battery 56 has a circuit wire connection 57 with bearing 6 and another circuit wire connection 58 with conductor rod 42. A switch 59 controls said wires. One end of

magnet 12 has a circuit wire connection 60 with cable fastener 11, the other end of said magnet being connected with a circuit wire 61 that extends through the car 9 and connects with the binding post 47 of conductor strip 46 that is seated in floor plate 45. Binding post 52 of the contact end of lever 50 has a wire connection 62 with hand operated bar 40. This arrangement provides a circuit from battery 56 through bearing 6, pulley 7 and cable 12^a to one end of magnet 12, and from battery 56 through conductor rod 42, roller 41 and bar 40 to wire 62, lever 50, conductor strip 46, wire 61 to the opposite end of magnet 12. It will therefore be seen that normally magnet 12 is energized so that its oppositely projecting piston rods or cores 18 are caused to hold the frame that supports gears 30 out of contact with the well racks. And also that the magnet attracts collars 33 so that rods 35 are also held by the magnet against the tension of springs 38. In the event of the cable 12^a breaking, the circuit will be broken, releasing piston rods 18 so that springs 38 will automatically slide plates 26 outward and cause gear wheels 30 to mesh with the well racks. As the car descends, piston rods 18 will be reciprocated in the compartments of magnet 12 through their eccentric connections with disks 31 and such reciprocations will be opposed by the air within said compartments acting upon the piston heads 19, causing the reciprocations to be slow and similarly affecting gear wheels 30, thereby causing the descent of the car 9 to be slow and gradual. Obviously the cushioning of the pistons is caused by the alternate intake and exhaust of the air in the ends of the compartments through pipes 20—22.

In connection with the above described automatically acting feature of the invention, it will be understood that in the event of cable 12 slipping or if the car be caused to fall in any other way without the circuit being broken, bar 40 may be manipulated from within the car by pulling on its handle 40^a so that roller 41 will be separated from conductor rod 42, thereby breaking the circuit and causing the gears 30 to engage with the well racks.

The invention also provides means whereby the circuit is broken by an open door. As has been explained, tripping arm 54 of lever 50 is in the path of movement of door 55, so that when said door is open, it causes arm 54 to rock lever 50 so that contact lug 51 is separated from conductor strip 46.

In the modified form of the invention shown in Figs. 5 and 6, the actuating rods 64 of the plates 26 have an armature 65 at their free end, said armatures being normally held to the poles of the horseshoe magnets 66—66^a. A separate cushion cylinder 67 is provided for each piston, said

cylinders having valve controlled pipes 68-69 at their ends. One of the magnets 66 has a circuit wire connection 70 between one of its poles and the cable fastener 11, 5 and the two magnets have opposite poles connected by a circuit wire 71. One pole of magnet 66^a has a wire connection 72 with the frame 39 of manual operable circuit breaker bar 40. In this modified form of the 10 invention, bar 40 is provided with a pin 73 that is engaged by the slotted end 74 of a tripping lever 75 that is pivotally connected to frame 39 and has its free end projecting into the path of movement of the car door 15 55 so that when said door 55 is open, it rocks lever 75 and thereby slides bar 40 so that its roller 41 is out of contact with conductor rod 42.

The mechanism of the modified form of 20 the invention performs the same functions as that described in connection with the preferred form of the invention—that is, automatically controls the descent of the elevator car in the event of cable 12 breaking; provides for the circuit being broken manually 25 by sliding bar 40 in frame 39, and provides means for automatically breaking the circuit when the car door is open.

What we claim as our invention is:—

30 1. A device of the character described comprising a car, rotatable well grippers slidably mounted on said car, magnetic means for rendering said grippers inactive, means for sliding said grippers to an operative position when released from said magnetic means, and pneumatic means for opposing the rotation of said grippers when in an operative position.

2. A device of the character described 40 comprising a car, rotatable grippers slidably mounted thereon, magnetic means for holding said grippers in an inoperative position, means for sliding said grippers to an operative position when released by said magnetic means, and means opposing the rotation of said grippers when in an operative position.

3. A device of the character described 50 comprising an elevator car, well grippers mounted thereon, magnetic means for normally retaining said grippers in an inoperative position, means for automatically causing said grippers to assume an operative position when released from said magnetic means, and pneumatic means for causing said grippers to permit a slow descent of the car when said grippers are in an operative position.

4. In a safety device for elevator cars, 60 the combination with the well and the car, of magnetically restrained rotatable well grippers carried by the car, means for causing said grippers to engage the well when released from said magnetic restraint, and cushioning means for causing said well grip-

pers to permit a slow descent of the car when said grippers are engaged with the well.

5. In a safety device for elevator cars, the combination with the well racks and the car, 70 of rotatable gear wheels slidably mounted on said car, magnetic means for normally holding said gears disengaged from said racks, means for automatically sliding said gears to engagement with said racks when 75 released from said magnetic means, and pneumatic means opposing the rotation of said gears when engaged with said racks.

6. A safety device for elevator cars comprising a car, rotatable well engaging gear 80 wheels slidably mounted thereon, magnetic means for rendering said gears inactive, means for sliding said gears to an active position when released from said magnetic means, and means opposing the rotation of 85 said gears when rendered active.

7. In a safety device for elevator cars, the combination with the well and the car, of slideways carried by said car, a support 90 slidable on each slideway, well engaging members carried by each support, magnetic means for holding said supports in position so that their well-engaging members will be held inactive, means for sliding said supports to cause the members to engage the 95 well when released from said magnetic means, and means for causing said well-engaging members to permit a slow descent of the car when engaged with said well.

8. In a safety device for elevator cars, the 100 combination with the well racks, the car, and the hoisting cable thereof, of rotatable rack engaging gear wheels slidably mounted on said car, a magnet on said car adapted to hold said gears disengaged from said 105 racks, a circuit including said cable and magnet, automatically acting means causing said gears to engage said racks when said circuit is broken, and means opposing the rotation of said gears when engaged with 110 said racks.

9. In a safety device for elevator cars, the combination with the well, the car, and the hoisting cable, of well grippers carried by 115 said car, a magnet controlling said grippers, a circuit including said magnet, a part of said well and said cable, means for automatically engaging said grippers with said well when said circuit is broken, a circuit breaker in said car and adapted to break said circuit when the car door is open, and means whereby said circuit breaker may be manually operated to break said circuit.

10. In a safety device for elevator cars, the combination with the well and the car, and the hoisting cable thereof, of a hollow magnet carried by said car, supports slidable on said car, a shaft carried by each support, a well engaging gear wheel carried by one portion of said shaft, a disk carried by 125 130

another portion of said shaft, cores slidable in said magnet, link connections between said cores and said disks, means for sliding said supports to cause their gears to engage said well when said cores are released by said magnet, a piston head for each core, said heads being slidable in said magnet, and a circuit including said magnet and cable.

10 11. In a safety device for elevator cars, the combination with a car of a hollow magnet mounted thereon and divided into two compartments, an intake pipe for each end of said compartments, a piston slidable in each compartment, a rod for each piston, a well gripper operated by each rod, and means for rendering said grippers active when said magnet is deenergized.

12. In a safety device for elevator cars, 20 the combination with the well grippers, of combined magnetic and pneumatic means which normally render said grippers inactive and cause the same to permit a slow descent of a car when said grippers are 25 active.

13. In a safety device for elevators, the combination with an elevator car, of a fluid

compressor carried by the car and adapted to be operated by the momentum thereof, a movable power transmitting member operatively connected to said compressor, a stationary member, and means operating upon an accidental falling of the car to connect the power transmitting member to the stationary member and thereby effect the 35 operation of the compressor.

14. In a safety device for elevators, the combination with an elevator car, of a fluid compressor carried by the car and adapted to be operated by the momentum thereof, an operating connection for said compressor, a stationary member, and means operating upon the breaking of the elevator cable for throwing said connection into engagement with the stationary member to thereby 40 cause the operation of the compressor.

In testimony whereof we hereunto affix our signatures in presence of two witnesses.

CLARENCE E. BAUMER.
BERTHA BAUMER.
